CLAIM

The ornamental design for a race flag feature for a radio frequency identification tag antenna layout, as shown and described.

DESCRIPTION

This design patent application may be found to be related to co-pending U.S. Design patent application Ser. No. 29/220, 504 filed on Dec. 30, 2004 in the name of inventor Ronald A. Oliver, entitled “Radio Frequency Identification Tag Antenna Assembly”, commonly owned herewith.

This design patent application may be found to be related to co-pending U.S. Design patent application Ser. No. 29/220, 493 filed on Dec. 30, 2004 in the name of inventor Ronald A. Oliver, entitled “Radio Frequency Identification Tag Antenna Assembly”, commonly owned herewith.

Furthermore, this design patent application may also be found to be related to co-pending U.S. Design patent application Ser. No. 29/220,496 filed on Dec. 30, 2004 in the name of inventor Ronald A. Oliver, entitled “Radio Frequency Identification Tag Antenna Assembly”, commonly owned herewith.

FIG. 1 is a top plan view of a race flag feature for a radio frequency identification tag antenna layout showing a first embodiment of my new design; and,

FIG. 2 is a top plan view of a race flag feature for a radio frequency identification tag antenna layout showing a second embodiment of my new design.
